[57] CLAIM

The ornamental design for a battery filling stand, substantially as shown and described.

DESCRIPTION

FIG. 1 is a perspective view of a battery filling stand, showing my new design,

FIG. 2 is a front elevational view of said stand,

FIG. 3 is a side elevational view thereof, and

FIG. 4 is a rear elevational view thereof.

The side of the stand not shown is a mirror image of the side shown.

FIG.3.

FIG.4.
